UNITED STATES PATENT OFFICE.

DANIEL L. GULTON, OF EVERETT, MASSACHUSETTS, ASSIGNOR TO GULTON MANUFACTURING CORPORATION, A CORPORATION OF VERMONT.

SAFETY CRANKING DEVICE FOR INTERNAL-COMBUSTION MOTORS.

Application filed May 25, 1925. Serial No. 32,640.

My invention relates to a device designed to afford protection to the operator from the effects of back-firing of the motor, and it has been the special object of my invention 5 to make a device which shall be strong, simple, and sure in operation and which may be cheaply and easily manufactured.

My device may be best understood by reference to the accompanying drawings in 10 which—

Fig. 1 is a front view of my device attached to a motor car of which a part of the front of the frame and radiator are shown.

15 Fig. 2 is a front view of my device with the handle thereof partly broken away.

Fig. 3 is a side view of my device.

Fig. 4 is a side view partly in section on line 4—4 of Fig. 2.

20 Fig. 5 is a front view with the front plate, shown in Fig. 4 and Fig. 6, removed.

Fig. 6 is a back view of the front plate.

Fig. 7 is a sectional view on line 7—7 of 25 Fig. 4, viewed in the direction of the arrow.

Fig. 8 is a sectional view on line 8—8 of Fig. 4, viewed in the direction of the arrow.

Fig. 9 is a sectional view on line 9—9 of 30 Fig. 4, viewed in the direction of the arrow.

Fig. 10 is a sectional view on line 10—10 of Fig. 5 showing the locking plug out of 35 operative position.

Fig. 11 is a view similar to that of Fig. 10 except that the parts are relatively placed 40 to show the locking position of the locking plug with respect thereto.

Referring now more specifically to the drawings, A is a motor drive shaft provided 45 with an enlarged hub a integral therewith, having a black flange a¹, also integral therewith (see Fig. 4). The hub a is slightly enlarged in its portion adjacent to said flange a¹ and is surrounded in this portion by a free but closely fitting ring B having 50 features of construction to be later described. A heavier ring C is freely but closely fitted on the hub a, this ring C having an annular flange c butting against the enlarged portion of the hub a and partially embraced 55 by the ring B. This ring C also has details of construction to be later described. The rings B and C are retained on the hub a by means of annular plate D which forms an outer flange of the hub a. The plate D has 60 an annular flange d which embraces the end

of the drive shaft A and is made fast thereto by means of the pin E which passes through holes in flange d and shaft A.

An annular housing F freely surrounds the ring B and adjacent flange a¹, there being a slight shoulder on the side of the annular housing F adjacent to the flange a¹ to prevent movement of the housing past the flange (see Fig. 4). The housing F has a downwardly extending lug f which is provided with a hole through which passes a bolt G which enters a hole in the fixed frame H of the automobile and is secured therein by means of nut g.

The ring C is surrounded by an annular housing I which overlaps and freely embraces on one side the housing F and on the other side the plate D. This ring C is provided with shoulders on its inner side whereby it is retained against lateral displacement by plate D and housing F. Thus both housings F and I are retained between flange a¹ and the opposite flange-forming plate D. A crank i is integral with housing I and is provided with a handle i¹.

The ring C is provided with a plurality of cylindrical holes c¹ (best illustrated in Fig. 7), aligned as cords with respect to the circular periphery of the ring C. These holes c¹ each contain a ball c² fitting rather loosely therein. When the holes c¹ are in such position that gravity tends to eject the balls c² therefrom the balls c² will slightly enter shallow pockets i² in the inner surface of annular casing I. These pockets i² are preferably twice as numerous as the holes c¹ so that a slight relative movement of casing I with respect to ring C will cause one or more of balls c² to become seated in an opposite pocket i² which is shaped to fit the surface of the ball c².

Extending through ring C in horizontal planes but with an anti-clockwise slant from back to front, and equidistant from the centre of axle A are a plurality of cylindrical holes c³ in which are slidably fitted plungers J, the forward ends j of which are somewhat beveled and rounded and the opposite ends of which are flat surfaces. The forward ends j are adapted, when the plungers J are thrust forward, to enter corresponding pockets d¹ in the inner surface of annular plate D. These pockets d¹ have surfaces contoured to closely engage the advanced side of the ends j of the plungers.

J. The back surface of ring C is provided with extensions c^4 (see Figs. 10 and 11), which are angularly set to support the rear of plungers J.

- 5 The flat ends of plungers J are seated each upon one of a series of inclined surfaces b (see Fig. 8 and Fig. 10) upon the front face of ring B. These surfaces b are much longer than the diameter of plungers 10 J and form a series of recesses having curved back walls b^1 against which may contact corresponding extensions c^4 of the ring C. These recesses formed by inclined surfaces b and back walls b^1 are deep enough to permit 15 the plungers J to retire far enough so that their rounded ends j are wholly out of contact with pockets d^1 .

Ring B is provided with a series of cylindrical holes b^3 (see Fig. 9) of similar arrangement to those holes c^4 in ring C. In 20 these holes b^3 are loosely fitted balls b^4 each of which is normally thrust outward by a coil spring b^5 mounted in hole b^3 and seated against the bottom of the hole. Hence, balls 25 b^4 always bear upon the inner surface of housing F.

The operation of my device is as follows:—To crank the motor crank i is rotated with a clockwise motion. This will impart 30 a like motion to ring C through the locking action of such of balls c^2 as have been caused by gravity to enter pockets i^2 in housing I. The continued clockwise of ring C will cause the rear ends of plungers J to slide along 35 the adjacent slanting surfaces b of ring B thus projecting the plungers J until each enters a pocket d^1 in plate D, (see Fig. 11) thus locking plate D and ring B together so that each is rotated through the driving 40 force of ring C operating upon the plungers J mounted therein. Thus, through the power applied to plate D which is fast on the shaft A, the shaft A is rotated to start the motor. Upon the normal starting of the 45 motor the plate D, instead of being a driven part, becomes a driving part with like clockwise motion. The ring C does not become a driven part as might be supposed as the immediate suspension of cranking force causes 50 ring C to lag slightly in its clockwise motion thus permitting the rearward ends of plungers J to run down thru the inclined surfaces b of ring B, thereby relieving rings C and B of the rotation force of plate D.

55 Let us suppose now that back-firing of the motor occurs during the cranking operation. This will impart an anti-clockwise motion to the shaft A and plate D. This will force the retirement of the plungers J as ring B becomes 60 stationary in the presence of this rotative influence thereon through plungers J, as the balls b^4 are rolled outward into locking engagement with the stationary housing F. The stopping of ring B permits plungers 65 J to slide back on their respective inclined

supports during the back rotation of ring C, into the position shown in Fig. 10, which backward sliding is forced by the curved sides of the pockets d^1 upon the rounded ends of plungers J as the plate D is driven by the 70 motor in an anti-clockwise direction, thus releasing the plungers J from contact with plate D and freeing the parts back of plate D from its influence and eliminating all anti-clockwise rotative force upon such parts and 75 therefore "back kick" in the crank i is prevented. The initial "back kick" of the system before plungers J have fully retired is so absorbed by the yielding frictional influences upon plungers J that no undue 80 violence thereof reaches the hand of the operator.

It will be readily understood that if shaft A, instead of being the main shaft of the motor, is connected therewith through the medium of the usual spur clutch, a sliding movement of shaft A must be permitted in which event nut h would not be used on bolt H and, instead of bolt H a pin would be used which pin would be loosely 90 embraced by either lug f or frame H, so that the safety crank and its shaft might be slid forward or back while maintaining the locked relation of housing F with respect to the frame H. With such construction 95 housing I and ring C may well be unitary as the normal starting of the motor in the direction of cranking movement will cause a severance of the connection of shaft A with the motor and hence no one-way clutch 100 means with respect to ring C and housing I are necessary. Nevertheless, I prefer to have the one-way clutch relationship between parts C and I as this permits "rocking" of crank i to bring it into the most convenient 105 position for exerting the cranking force thereon.

Although I have found it most convenient and inexpensive to employ the well known Horton type of one-way clutch between ring B and housing F because locking engagement is seldom here effected and locking strains are never great, nevertheless, it will be readily apparent that my stronger type of one-way clutch provided for ring C and 115 housing I may be substituted.

I claim:

1. In a device of the character specified the combination of two rotatable members having opposed surfaces provided with inset portions, and a separate rotatable connecting means adapted to enter said inset portions and lock said rotatable members by positive engagement therewith in a manner whereby they may be rotated together in one direction of rotation, said connecting means being adapted to become disengaged automatically from one of said rotatable members upon the opposite rotation of one of said rotatable members.

2. In a device of the character specified the combination of a rotatable one-way clutch member provided with an inset portion having an inclined surface, a second rotatable member provided with a pocket, a third rotatable member arranged to receive cranking force mounted between said rotatable members, said third rotatable member being provided with a slanting hole, a plunger slidably mounted in said hole and arranged to bear at one end upon said inclined surface and to be projected by sliding contact therewith until its opposite end enters the pocket in said second rotatable member, thus forming a driving connection between said rotatable members.

3. In a device of the character specified the combination of a hub, a ring rotatably

mounted on said hub and provided with an inset portion having a slanting surface, an annular casing surrounding said ring, means whereby said casing is retained in fixed position, a one-way clutch means between said ring and said casing, a plate fast on said hub and provided with a pocket, a cranking means rotatably mounted on said hub between said ring and said plate, said cranking means being provided with a slanting hole, and a plunger freely mounted within said hole arranged to bear at one end of said slanting surface on the inset portion of said ring and to be projected by sliding contact therewith so that its opposite end may enter said hole in said plate.

DANIEL L. OULTON.
